[57] CLAIM

The ornamental design for a foldable table, as shown and described.

DESCRIPTION

FIG. 1 is a perspective view of the subject foldable table;

FIG. 2 is a right side elevational view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a top plan view thereof;

FIG. 8 is a perspective view thereof, when folded; and, FIG. 9 is a perspective view thereof, when a beach umbrella is installed.

The broken line disclosure of an umbrella in FIG. 9 is for illustrative purposes only and forms no part of the claimed design.
